AIR HEATER

Joseph Frank Herbert, Audubon, N. J.

Application March 3, 1936, Serial No. 66,909

7 Claims. (Cl. 126—110)

This invention relates to the class of hot air furnaces and pertains particularly to an air heating furnace of the forced air circulating type to be used in conjunction with any type of heating means, such as a pressure type domestic fuel oil burner or the like.

A primary object of the present invention is to provide an improved air heater of compact design which is capable of efficiently heating large quantities of air and at the same time because of its compactness being adapted to be moved about.

Another object of the invention is to provide an improved air heating furnace having a novel heat transfer unit whereby the maximum heat units of the fuel employed will be extracted from the burning fuel gases.

A still further object of the invention is to provide a novel air heating furnace wherein the air to be heated is forced to move downwardly between air transfer plates of hollow construction, through which plates the products of fuel combustion pass upwardly, and wherein the downwardly flowing air is divided and a portion of it passed across a water container so that the air will be humidified.

A still further object of the invention is to provide an air heating furnace having built thereinto an air circulating unit whereby unheated air will be drawn in and circulated through the heat transfer portion of the structure and discharged from the furnace directly into the room in which the furnace is placed or into distributing pipes as desired.

The invention will be best understood from a consideration of the following detailed description taken in connection with the accompanying drawings, with the understanding that the invention may be changed or modified so long as such changes or modifications mark no material departure from the salient features of the invention as expressed in the appended claims.

In the drawings:

Figure 1 is a view in elevation of a furnace structure embodying the present invention;

Figure 2 is a vertical sectional view taken on the line 2—2 of Figure 3;

Figure 3 is a sectional view taken on the line 3—3 of Figure 2;

Figure 4 is a horizontal section taken on the line 4—4 of Figure 2;

Figure 5 is a section on the line 5—5 of Figure 2;

Figs. 6 and 7 are sectional views taken respectively on line 6—6 and 7—7 of Fig. 2.

Referring now more particularly to the drawings wherein like numerals of reference indicate corresponding parts throughout the several views, the numeral 1 indicates generally the body or housing of the furnace structure embodying the present invention, the same being preferably of rectangular cross section as illustrated and having a front wall 2 provided with the plate 3 through the center of which an aperture is formed for the introduction of a fuel burner nozzle 4. The wall construction of the furnace body 1 may be of any suitable type, such as metal having an insulation outer covering as is commonly employed.

Secured in the lower part of the body of the furnace housing is a floor 5 which extends from the front wall 2 to a point short of the back wall 6 thus leaving an area 7 bordered on one side by the back wall 6 and at the two ends by the side walls 8 and at the front by a low upstanding wall 9 which is formed integral with the bottom or floor 5 at its back edge and which extends the full width of the furnace. The bottom wall 5 is of a width at its rear equal to the interior width of the furnace structure and tapers slightly toward the front as illustrated in Figure 4, and thus leaving open side areas 10. These tapering sides of the bottom have vertical walls 11 formed integral therewith and are connected by a top wall 12 which, as shown in Figure 2, slopes upwardly through half of its length from the front wall of the furnace structure toward the back and is then inclined downwardly at a sharp inclination to meet the hanging baffle wall 13 which has its lower edge spaced from the bottom 5 and which is in spaced relation with the wall 9. There is thus formed the fire box or combustion area 14 and, as shown in Figure 2, the fuel burner nozzle 4 is directed toward the lower part of the hanging wall 13 and against the downwardly inclined under side of the back part of the top wall 12.

Extending transversely of the furnace floor in the fire box 14 is an adjustably positioned upstanding baffle wall 16 which is placed forwardly of the wall 13 so that suitable passageway is provided for the escape of products of combustion into the area between the walls 9 and 13 at the back part of the furnace. The position of this baffle wall 16 is regulated when the heating structure is installed for use.

Opening through one side of the furnace structure and through a wall 11, is a passage forming structure 17 which opens into the fire box at one end and which has its outer end closed by the gravity controlled door 18. This structure 17

14 provides an escape for any suddenly developed pressure in the fire box 14 such as might occur if an excess of gas collected in the box and was suddenly ignited so that the suddenly developed pressure therein could not conveniently escape through the usual gas escape passages.

Arranged above the top wall or roof 12 of the combustion chamber 14 is a horizontal wall 19 which extends across the width of the furnace structure and which is joined at its front edge with the lower edge of a vertical inner front wall 20 and at its back edge with a vertical inner rear wall 21. The area between the wall 19 and the roof 12 of the combustion chamber together with the area between the inner front wall 20 and the outer front wall 2 of the structure form together a hot air escape passage which is indicated by the numeral 22, and this passage is in communication with the areas 10 at the sides of the combustion chamber.

The area between the inner walls 20 and 21 and the wall 10, forms a chamber 23 the top of which is covered by the top wall 24 of the furnace structure and this top wall has an opening therein in which is removably fitted a frame 25 which is filled with a suitable air cleaning or filtering material of non-combustible character such as steel wool or the like which is designated by the numeral 26. Within the chamber 23, which constitutes the fan and motor housing, is an electric motor 27 and a fan 28, the air intake side of which opens into the housing or chamber 23 while the discharge pipe 29 thereof opens through the inner rear wall 21 into the area lying between this wall and the back wall 8.

Disposed in the area between the walls 21 and 8 is a heat exchange unit which is generally designated by the numeral 30 and which comprises a plurality of flat tubes 31 arranged in relatively close side by side relation and maintained in the desired spaced relation by the ribs 32 which are pressed outwardly from the side walls thereof throughout a portion of the length of the walls, as illustrated in Figures 2 and 5. The areas between these flat tubes are closed at the top end of the unit while the top ends of the tubes are open and these top ends are cut at an incline as shown in Figure 2 so as to discharge into the area 33 which is in communication with the flue 34 or gas outlet 34. The lower ends of the tubes open into the area between the walls 9 and 13 and receive the products of combustion passing from the combustion chamber 14 beneath the baffle wall 13. As shown in Figure 2, the lower ends of the tubes 31 are cut into an inverted V, as indicated at 35, and the areas between the lower ends of the tubes are closed by the V-shaped walls 36. One side of the V-shaped cut out portion 35 terminates short of the rear edges 60 of the tubes and rests upon the top of the wall 9. It will thus be seen that there remains a portion of each tube 31 which extends across the area of the wall 9 and the back wall 8 and this remaining portion of the lower end of each tube is closed but the space between the tubes over this portion is left open. From this it will be apparent that air driven by the fan 28 through the opening in the top of the wall 21 into the areas between the tubes, will flow downwardly until it strikes the dividing plates 38 between the tubes whereupon a portion of it will be deflected by the plates 38 into the passageway 22 which leads across the top wall 12 of the combustion chamber and another portion will flow downward-

ly between the tubes into the area 7 beneath the bottom wall 8. This bottom wall 8 is provided with a plurality of fins 37 which, as illustrated in Figure 4, are curved to guide the air forwardly to the areas 10 from which it will flow upwardly into the passage 22, and the back surface of the wall 9 also has vertically arranged fins 38 thereon which keep the air spread out and prevent it flowing in a narrow path.

The back wall 6 of the furnace structure is provided with an opening 39 for the introduction into the area beneath the bottom 8 of the combustion chamber, of a pan 40 which has an open top and which is intended to contain water at all times while the furnace is in operation.

This pan has its top spaced from the lower edges of the air guiding fins 37 and is adapted to have its top closed by a suitable means, such as a plurality of louver blades 41 which are oscillatably mounted therein and which may be controlled by a suitable lever 42 which may be manually actuated or may have any suitable mechanical means connected therewith for effecting this actuation in accordance with the degree of humidity of the air of the room in which the furnace is located.

In the area lying at the rear of the combustion chamber 14 and defined by the vertical walls 9 and 13, there may be located a suitable pipe or coil 43 for heating water for domestic use and also located in this area is a burner 44 of the type suitable for burning fuel gases. This burner may be used as an auxiliary to the burner which has its nozzle 4 extended through the front wall of the combustion chamber in the event that the liquid fuel burning unit breaks down or has to be kept out of use for any reason during a period when it is necessary that the furnace be kept in operation.

At one end of the area into which the combustion chamber discharges, the wall of the furnace is provided with an opening 45 which is covered by a door 46 and which provides a means for cleaning out this portion of the furnace or for reaching the burner 44 or water pipe 43 if occasion demands. The top wall 24 is provided with an opening over the area in which the tubes 31 are disposed which is covered by a removable door 24'. By means of this opening the areas between the tubes may be reached for cleaning.

In order that the air flowing downwardly between the flat tubes 31 and into the area over the roof of the fire box or combustion chamber 14 may be kept spread out so as to pick up as much heat as possible from the fire box, the roof of the fire box is provided with a series of fins 47. The wall 21, in addition to having the opening at its top for the passage of air therethrough by the fan 28, also has an opening or openings in its lower portion which discharge from the areas between the tubes 31 into the area between the combustion chamber wall 12 and the inner horizontal wall structure 10.

The material 26 in the air inlet opening leading to the fan chamber 23 may be of any suitable character to clean the air. One method which may be employed is to saturate the steel wool 26 with oil so that the air passing therethrough will have any dust particles picked up extracted therefrom and will pass between the flues of the heat exchanger in a clean condition.

While the description and illustration have been confined to the furnace structure per se it will be obvious that the operation of the same may be readily controlled by any of the automatic devices

at present on the market for governing the operation of furnaces so that when the air within the furnace reaches a predetermined temperature the burner operation may be shut down or shut off as required and also when the room temperature reaches the desired degree the operation of the furnace may be completely shut off. For the control of the burner mechanism in accordance with the flue temperature of the furnace, there is shown 10 in connection with Figures 1 and 3 a thermostat device which is indicated by the numeral 48. These control devices for the burner and for the air circulating blower may be so arranged that when the controlling room thermostat calls for 15 heat, the burner mechanism and the air blowing mechanism will start operating. When the heated air within the furnace reaches approximately 230°, the control device 28 will shut off the burner but the air circulating device will continue to operate 20 to force the heated air from the passage 22 until the air temperature in the furnace drops to approximately 200°. At this point the burner will again be started up and these cycles will continue until the desired room temperature is reached 25 after which the room thermostat will operate to shut off the burner and the air circulating fan or blower will operate until the furnace temperature drops to 90° when it too will cease operating.

I claim:—

- 30 1. In an air heater, a housing body, a fuel combustion chamber disposed in said body and having top, bottom and side walls, said side walls being in spaced relation with the side walls of the housing body whereby air may flow from beneath the combustion chamber to the space above the same, an upwardly directed outlet to the rear of said combustion chamber, an inner rear wall in said housing body extending upwardly through the housing body from the combustion chamber at one side of said outlet and forming with the housing body rear wall a vertically extending chamber into which said outlet is directed, a heat transfer unit comprising a plurality of vertically disposed flat tubes arranged in spaced relation in said chamber between the housing body rear wall and the inner rear wall and over said outlet, said inner rear wall having openings leading therethrough from the spaces between the tubes to the space over the top wall of the combustion chamber, said tubes being open at their upper and lower ends for the passage of products of combustion therethrough, means closing the spaces between the tubes at the upper and lower ends thereof, means for forcing air downwardly between the tubes for discharge onto the top wall of the combustion chamber, means for leading off the products of combustion from the upper ends of the tubes, and means for leading off the heated air from the housing.
- 60 2. An air heater comprising a housing, a combustion chamber in the lower part of said housing, which includes a bottom wall, side walls and a top wall, said side walls being partly in spaced relation with the side walls of the housing, said bottom wall being spaced from the bottom of the housing terminating short of the back wall of the housing and having an upstanding wall spaced from the housing back wall, said top wall terminating short of the upstanding wall to form an outlet for the combustion chamber, a wall extending transversely of the housing over and in spaced relation with the top wall of the combustion chamber and forming a horizontal air passageway therewith, a vertical wall extending from said transverse wall upwardly in spaced relation

with said housing back wall, a plurality of flat tubes disposed in spaced side by side relation between said vertical wall and the housing back wall over the said outlet, said tubes being open at their upper and lower ends and receiving products of combustion in their lower ends, means closing the spaces between the tubes at the upper ends, means closing the areas between the tubes at their lower ends from the terminal edge of the top wall transversely to said upstanding wall, the spaces between the lower ends of the tubes being open between the said upstanding wall and the back wall of the housing, means for creating a downward flow of air between the tubes for discharge therefrom into said air passageway, a portion of the air being delivered to the space between the housing back wall and said upstanding wall to flow beneath and up over the sides of the combustion chamber, means for carrying off the products of combustion from the upper ends of the tubes, and hot air outlet means for the housing.

3. In an air heater, a casing having a vertical chamber, means forming a combustion chamber in the lower part of the casing and having an outlet directed upwardly into the lower part of the first chamber, said first chamber having a products of combustion outlet at the upper part thereof, a plurality of vertically arranged broad flat tubes in the chamber which terminate at their lower ends over and extend across said combustion chamber outlet, the tubes being spaced apart and having their ends open, means closing the spaces between the tubes at the ends thereof, a heated air outlet at an elevation above the combustion chamber, means for forcing air into the spaces between the tubes adjacent the tops thereof, and means between the lower ends of the tubes for dividing the path of air travel into two streams over the outside of and above and below the combustion chamber to the heated air outlet.

4. In an air heater, a casing, a pair of vertically arranged spaced walls therein and a horizontal wall connecting the spaced walls whereby to form a center chamber and two vertical side chambers, one of said side chambers constituting a heated air passage having an outlet, said side chambers opening into the lower part of the casing beneath said horizontal wall, means forming a combustion chamber having a top wall spaced from said horizontal wall and an outlet directed upwardly into the other side chamber, a plurality of spaced flat tubes in said other chamber which are open at their ends and form products of combustion conducting means between the combustion chamber outlet and an outlet at the upper part of the said other side chamber, said tubes having the spaces between their ends closed, and means in said center chamber for forcing air downwardly through the spaces between the tubes for discharge therefrom into the space between the horizontal wall and said top wall and thence to said heated air passage.

5. In an air heater, a casing, a pair of vertically arranged spaced walls therein and a horizontal wall connecting the spaced walls whereby to form a center chamber and two vertical side chambers, one of said side chambers constituting a heated air passage having an outlet, said side chambers opening into the lower part of the casing beneath said horizontal wall, means forming a combustion chamber having a top wall spaced from said horizontal wall and an outlet

directed upwardly into the other side chamber, a plurality of spaced flat tubes in said other chamber which are open at their ends and form products of combustion conducting means between the combustion chamber outlet and an outlet at the upper part of the said other side chamber, said tubes having the spaces between their ends closed, means in said center chamber for forcing air downwardly through the spaces between the tubes for discharge therefrom into the space between the horizontal wall and said top wall and thence to said heated air passage, and means facilitating conducting a portion of the downwardly flowing air beneath the combustion chamber and about the sides thereof prior to its entry into said heated air passage.

6. In an air heater, a casing, a pair of vertically arranged spaced walls therein and a horizontal wall connecting the spaced walls whereby to form a center chamber and two vertical side chambers, one of said side chambers constituting a heated air passage having an outlet, said side chambers opening into the lower part of the casing beneath said horizontal wall, means forming a combustion chamber having a top wall spaced from said horizontal wall and an outlet directed upwardly into the other side chamber, said last outlet being adjacent a rear wall of the combustion chamber and said rear wall being spaced from a wall of the casing forming therewith a passage leading downwardly from said other chamber to a space beneath the combustion chamber, a plurality of spaced flat products of combustion conducting tubes extending vertically in the said other chamber in the top of said rear wall and having their lower edges extending across the same, the ends of the tubes being open, means closing the spaces between the upper ends of the tubes through the entire width of the tubes, means closing the spaces between the lower ends of the tubes only from one side of said combustion chamber outlet to

the other, the spaces between the tubes at the lower ends thereof opening into the space between said horizontal wall and said top wall, and means in said center chamber for forcing air downwardly through the spaces between the tubes 5 and thence to the space above and beneath the combustion chamber and to the heated air passage.

7. In an air heater, a casing having back, bottom and side walls, a combustion chamber disposed within the lower part of the casing in spaced relation with the bottom wall and having a rear wall in spaced relation with the casing back wall, said chamber rear wall extending the full width of the casing between the side 15 walls, air passageways between the sides of the chamber and the side walls of the casing, said combustion chamber having an upwardly directed outlet immediately adjacent its rear wall, a vertical chamber extending the full width of 20 the casing between the side walls and having an outlet at its upper end and having the combustion chamber outlet directed upwardly thereto, means forming a plurality of products of combustion conducting passages from said combustion chamber outlet to the vertical chamber outlet, air conducting passages alternating with said first passages, means for effecting a down flow of air through the air conducting passages, means in the lower ends of the air conducting 30 passages for deflecting the down flowing air in two streams one of which passes over said combustion chamber and the other of which passes downwardly between the combustion chamber rear wall and the casing back wall to 35 the area beneath the combustion chamber, and a warm air outlet from the casing at an elevation above the combustion chamber, the air passing beneath the combustion chamber flowing to said last outlet by way of the passages 40 at the sides of the combustion chamber.

JOSEPH F. HERBERT.
